SERVING TONGS

Mario T. David, Los Angeles, Calif.

Application June 30, 1952, Serial No. 20,421

Term of patent 14 years

(Cl. D44—4)

To all whom it may concern:

Be it known that I, Mario T. David, a citizen of the United States and a resident of Los Angeles, in the county of Los Angeles, State of California, have invented a new, original, and ornamental Design for Serving Tongs, of which the following is a specification, reference being had to the accompanying drawing, forming a part hereof.

In the drawing,

Figure 1 is a perspective view of serving tongs, showing my new design;

Fig. 2 is a top plan view of the serving tongs in Figure 1, in closed position;

Fig. 3 is a side elevational view of the serving tongs shown in Fig. 2; and

Fig. 4 is a sectional view of the serving tongs taken along line 4—4 of Fig. 3.

I claim:

The ornamental design for serving tongs, as shown.

MARIO T. DAVID.
